UNITED STATES PATENT OFFICE.

ROBERT M. GLOR, OF ATTICA, NEW YORK.

STANCHION.

972,849.

Specification of Letters Patent. Patented Oct. 18, 1910.

Application filed November 28, 1908. Serial No. 464,916.

To all whom it may concern:

Be it known that I, ROBERT M. GLOR, of Attica, Wyoming county, New York, have invented a new and useful Improvement in 5 Stanchions, of which the following is a full, clear, and exact description.

My invention relates to improvements in stanchion construction, and the object of my invention is to produce a structure of this 10 character which is adapted to provide an absolutely secure but yet exceedingly easy fastening for cattle, which fastening will give them great freedom of movement but yet will hold them so that they cannot possibly 15 get loose accidentally.

My invention is intended further to produce a simple yet strong structure in which the cattle can be easily secured or as easily released.

20 To these ends, and with the general idea of making a comfortable, economical, strong, sanitary construction of the kind described, my invention consists of certain features of construction which will be hereinafter fully 25 described and claimed.

Reference is to be had to the accompanying drawings forming a part of this specification, in which similar reference characters indicate corresponding parts in all the 30 views.

Figure 1 is a rear elevation of the stanchion construction showing my improvements. Fig. 2 is an enlarged broken detail 35 longitudinal section of the stanchion, showing the same in position to release a cow or other creature. Fig. 3 is a detail view partly in section, showing the stanchion in locked position, and Fig. 4 is a horizontal section looking up on the line 6—6 of Fig. 5.

40 The stanchion has a framework 10 of a substantial character, consisting of the upper sill, top piece, and vertical studs, which can be of any necessary length, and which as usual in such structures, is arranged 45 so that the heads of the cattle stick through it. In this frame are mounted the stanchions, each comprising an upright 12, a base piece 13, a top piece 14 longer than the base, and a locking bar 15 which is pivoted 50 in the base and swings in the top piece 14. The base pieces and top pieces 13 and 14 are hollowed out in the center, or in other words are made of parallel strips having stops 13^a and 14^a at the outer ends. This 55 is shown clearly in Fig. 2. Thus the locking bar 15 swings freely in the base piece

13, and also in the top piece 14, the movement being limited by the stops 13^a and 14^a. At the top and bottom of the upright 12 are brackets 16 and 17 which project inward, 60 and which are journaled in the frame 10, as shown clearly at 18 and 19. The top bracket 16 is prolonged to form a buffer 20 against which the locking bar 15 swings when the stanchion is in locked position. 65

The most important feature of the invention is the catch 21, which is in the form of a flat plate secured to a handle 22 which is arranged transversely in the top piece 14, so that the latch can be operated by the handle if desired, although it locks automatically. Near its free end the catch 21 is provided with an offset 23 which is adapted to automatically engage the end of the locking bar 15 when the latter is swung into 70 vertical position against the buffer 20, and thereby the locking bar is held securely closed. It will be seen that it will be bound in all four directions between the two side walls of the top piece 14 and between the 75 buffer 20 and the offset portion of the catch 21. The bar is released by tilting the handle 22 and thus lifting the catch 21, and the bar can then be swung to the position shown in Fig. 2, and this causes the free end 23 80 of the catch to enter the recess 24 in the framework 10, and so the stanchion is locked in its released position. Thus it will be seen that when a creature is released from the 85 stanchion, the latter is locked so that it is 90 always in position for the creature to stick its head through between the bars 12 and 15 when driven in, and yet when the stanchion is locked so as to secure the creature, the latter then has a perfectly free movement of its 95 head, as the stanchion rotates on its bearings 18 and 19. I consider this feature of locking the stanchion against rotation when in released position, automatically, an important feature, and it will be seen that the 100 detail construction of the catch 21 can be departed from considerably without affecting the principle of the invention.

The stanchion is provided with off-set portions 25 which are secured to the outside 105 of the bar 12, as shown at 26, for the purpose of preventing a creature from sticking its head through the wrong side of the bar 12.

It will be seen from the foregoing description that I have produced a very simple, convenient, safe and sanitary structure,

well adapted to the use of cattle when arranged in a tie-up, as is customary

Having thus fully described my invention, I claim as new and desire to secure by 5 Letters Patent:—

In a stanchion, top and bottom members, a stanchion frame pivotally mounted between said top and bottom members, said frame comprising an upright, laterally extending members at the top and bottom of 10 said upright, each of said laterally extending members consisting of parallel arms, a locking bar pivoted within the lower arms and slidable within the upper arms, a re-

movable bolt rotatable in the upper arms 15 and having one end formed into a handle, and a metal plate fixed to said bolt and having an offset end, said offset end adapted to be pressed into a recess in the top stanchion member when the locking bar is swung open, 20 said locking bar being engaged by the under face of said plate and wedged in position and said offset end adapted to engage the end of said bar when the latter is closed.

ROBERT M. GLOR.
